UNITED STATES PATENT OFFICE.

WILLIS WHITFORD, OF VAWN, SASKATCHEWAN, CANADA.

ROTARY GRINDING AND POLISHING TOOL.

1,204,102.

Specification of Letters Patent.

Patented Nov. 7, 1916.

Application filed June 23, 1916. Serial No. 105,426.

To all whom it may concern:

Be it known that I, WILLIS WHITFORD, a citizen of the United States, residing at Vawn, in the Province of Saskatchewan and 5 Dominion of Canada, have invented certain new and useful Improvements in Rotary Grinding and Polishing Tools; and I do hereby declare the following to be a full, clear, and exact description of the invention, 10 such as will enable others skilled in the art to which it appertains to make and use the same.

This invention has for its object to provide an improved and efficient tool including a 15 novel type of rotary head or holder for detachably supporting various abrading and polishing tools.

Another object is the provision of means for rotatably supporting the head or holder 20 in the handle of the tool in such manner as to reduce friction and consequent wear of the parts to the minimum.

With these and other objects in view, the invention consists in the novel construction, 25 combination and arrangement of parts as will be hereinafter specifically described, claimed and illustrated in the accompanying drawings, in which:

Figure 1 represents a side elevation of the 30 improved tool, Fig. 2 represents a bottom plan view thereof, Fig. 3 represents a longitudinal sectional view through the tool, Fig. 4 represents a bottom plan view of the tool, the head or holder being removed, Fig. 5 35 represents a perspective view of several of the elements of the tool removed from the handle and detached, Fig. 6 represents a plan view of the tool, the cap being removed, and Fig. 7 represents a detail sectional view on the line 7—7 of Fig. 2.

Referring to the drawings in detail, wherein similar reference numerals designate corresponding parts throughout the several views, the numeral 10 indicates a hollow 45 handle of such external diameter as to be conveniently held in the hand of the operator and having one end enlarged, as indicated at 11, and provided with an annular flange 12.

A shaft 13 is rotatably supported in the 50 handle 10 and one end thereof protrudes through a cap 14 removably fitted upon the relatively small end of the handle and is adapted to be connected with a motor or 55 other driving mechanism (not shown). A nut 15 is fitted upon the shaft 13 and adjust-

ably secures a bearing member 16 engaging bearing balls 17, which latter are mounted in an annular groove 18 formed internally of the handle 10.

The end of the shaft 13 opposite the cap 14 is formed with a longitudinal slot 18', removably receiving a triangular key 19 and the slotted portion of said shaft is formed with external screw threads removably received within an internally screw threaded opening 20 formed axially within a circular head or holder plate 21. The head 21 is received within the annular flange 12 at the relatively large end of the handle and a 70 plurality of bearing balls 22 are arranged between the head and the handle and are adapted to co-act with the bearing balls 17 to rotatably support the shaft 13 and head 21 in the handle.

The head 21 is formed upon its inner surface with a diametrical slot 23 adapted to receive the key 19, whereby the head is locked against rotary movement with relation to the shaft 13. The outer portion of the head is 80 formed with a laterally projecting peripheral flange 24, having pairs of diametrically opposed lugs 25 adapted to engage in recesses formed in corresponding relation in an abrading or polishing implement 26, 85 which is of circular formation and is removably received within the flange 24 and is engaged with the head 21, as clearly shown in Fig. 3. The outer or working face of the implement 26 is of substantially conical formation and recesses 28 are formed in the edge of the implement and are adapted to receive inwardly directed pins 29, carried by leaf springs 30 attached to the flange 24 of the head, whereby the abrading or polishing implement is rigidly secured in position 90 upon the head 21.

What I claim is:

1. A polishing and grinding tool comprising a hollow handle, a shaft rotatably supported in said handle having one end slotted, a head removably secured to the slotted end of said shaft, and a sleeve fitted in said slot and non-rotatably engaged with said head.

2. A rotary tool comprising a hollow handle, a shaft rotatably supported in said handle having one end slotted, a head detachably secured to the slotted end of said shaft and having a diametrical slot therein, 110 and a substantially triangular key fitted in the slots in said shaft and said head for non-

2
rotatably securing the latter against rotary movement upon said shaft.

3. A tool comprising a handle, a shaft rotatably supported within said handle, a head detachably secured to said shaft having a laterally projecting flange, a surfacing element supported in said flange, and spring actuated pins carried by said flange and adapted to engage said surfacing element to secure the latter against removal.

4. A tool comprising a handle, having one end enlarged and provided with depending flanges forming an annular recess, a shaft rotatably supported in said handle, an apertured cap fitted over one end of said handle,

a head detachably secured to said shaft and partially fitted within the annular recess, and the depending flanges of the enlarged ends of the handle, and a surfacing element detachably secured to said head, said enlarged portion of the handle acting as a guide to prevent the hand from coming in contact with the surfacing element when in use. 20

In testimony whereof I affix my signature 25
in presence of two witnesses.

WILLIS WHITFORD.
